ELECTRIC LIGHT SOCKET

Abraham Wolf, New York, N. Y., assignor to
 Noma Electric Corporation, New York, N. Y., a
 corporation of New York

Application December 16, 1937, Serial No. 180,085

11 Claims. (CL. 240—10)

This invention relates to portable electric lighting outfits of the type used for Christmas tree ornamentation and for similar illuminated display purposes. More particularly, my invention relates to an improved construction for the electric light sockets used with such lighting outfits.

One of the objects of my invention is to provide an electric light socket construction of the character described, having novel means for attaching said sockets to a branch of a Christmas tree, or to any other support.

Another object of my invention is to provide an electric light socket of the character described and novel mounting means therefor, which shall comprise relatively few and simple parts, which shall be economical to manufacture, easy to assemble and which at the same time shall be highly efficient for the purposes intended.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible embodiments of this invention,

Fig. 1 is an elevational view of an electric light socket of the type used in Christmas tree lighting outfits and embodying my invention;

Fig. 2 is an enlarged cross-sectional view taken substantially on the line 2—2 of Fig. 1;

Fig. 3 is an elevational view of the socket only, shown in Fig. 1;

Fig. 4 is a bottom view of the Fig. 3 form of socket;

Fig. 5 is an enlarged perspective view of the supporting member only shown in Fig. 1;

Fig. 6 is an elevational view, partly sectional, of a socket illustrating a modified form of my invention;

Fig. 7 is a bottom view of the Fig. 6 form of socket;

Fig. 8 is an enlarged perspective view of the supporting member only, shown in Figs. 6 and 7;

Fig. 9 is an elevational view similar to Fig. 1 but illustrating another modified form of my invention;

Fig. 10 is an enlarged cross-sectional view taken on the line 10—10 of Fig. 9; and

Fig. 11 is an enlarged perspective view of the supporting member only, shown in Figs. 9 and 10.

Referring now in detail to the drawing and particularly to Figs. 1 to 5, there is shown an electric light socket of the type well known in the art, used on Christmas tree or similar portable display lighting outfits, and provided with a husk 20, of insulating material and lamp 21 and suitable lead wires 22 connected to the socket, in the manner well known in the art.

The outer wall of the husk 20 is provided with a relatively narrow raised portion 23, which may be integral therewith and which may be disposed parallel to the axis of the shell. The longitudinal edges 23a of the portion 23 may be inwardly tapered as shown for reasons which will soon become apparent.

For attaching the socket to any support such as for example the branch B of a Christmas tree, I have provided an attaching member 30, (see Fig. 5) comprising a strip of resilient material, bent over on itself to form two substantially parallel arms 31 and 32 interconnected by the loop 33. The arm 32 is preferably made flat to overlie the surface of the portion 23, and is provided with pairs of spaced tabs or guides 34 and 35, which may be formed of integral extensions bent over to define a guideway adapted to slidably receive therein the raised portion 23, with the guides 34 and 35 snugly fitting the tapered edges 23a of said raised portion to hold the member 30 frictionally captive on the socket.

The member 30 may be resiliently hooked over a branch B, the said branch being received between the arms 31 and 32. To insure a more positive gripping action of the member 30, either of the arms 31 and 32, such as for example the arm 32 as shown, may be provided with bent over side extensions 36 between the guides 34 and 35, the free edges of which are serrated as shown.

In Figs. 6 to 8 I have shown a modified form of my invention, in which the attaching member 30', instead of having the arm 32 provided with the tabs or guides 34 and 35, is provided with a pair of continuous guides 40, which are substantially contiguous with the length of the arms 32. The said guides 40 are angularly bent to conform to the tapered walls 23a, and are adapted to be slidably and frictionally received on the raised portion 23. To increase the gripping action of the member 30', the arm 32 may have portions 41 struck out therefrom, and provided with serrated edges, as shown in Fig. 8.

In Figs. 9 to 11, I have shown another modified form of my invention, in which the attaching member 50 comprises a pair of arms 51 and 55

52 of resilient material, similar to the arms 31 and 32 and interconnected by a loop 53. The arm 52 is provided with angularly bent over edge portions 54, provided with serrations to 5 provide better gripping action for the member 50. For attaching the member 50 to the socket, I provide an independent relatively rigid flat member 55, freely rotatably attached to the arm 52 by means of the pivot 56. The member 10 55 is provided with angularly bent over longitudinal edges 57, corresponding to the tapered walls 23a of the raised portion 23 and adapted to be frictionally received thereon.

It is seen from the above described construction that the member 50, after being attached to the socket, may be rotated about the pivot 56 to assume any desired angle before or after attachment to a branch.

It is also noted that the attaching members 20 30, 30' or 50 may be applied to the type of socket in which there is employed a bottom cap 60 which is screwed to the husk 20' and in such position serves to prevent downward sliding or undesired removal of the members 30, 30' or 50.

25 If desired, the arm 32 may be provided with one or more struck out portions defining pointed projections 70 adapted to become embedded in the top surface of the portion 23 to prevent the downward sliding of the member 30. Also, if 30 desired, detents 71 may be provided in the top surface of the portion 23 adapted to receive the projections 70 therein.

It will thus be seen that there is provided a device in which the several objects of this invention are achieved, and which is well adapted to meet the conditions of practical use.

As various possible embodiments might be made of the above invention, and as various changes might be made in the embodiments 40 above set forth, it is to be understood that all matter herein set forth or shown in the accompanying drawings is to be interpreted as illustrative and not in a limiting sense.

Having thus described my invention, I claim 45 as new and desire to secure by Letters Patent:

1. In an electric light holder, a husk of insulating material having a portion thereof raised above the outer surface, an attaching member comprising a single longitudinal strip of resilient material bent substantially in half to provide a pair of arms spaced from each other in superimposed aligned relationship adapted to grip a support therebetween, and means on one of said arms for slidably receiving therein said raised husk portion.

50 2. In an electric light holder, a husk of insulating material having a portion thereof raised above the outer surface, an attaching member comprising a strip of resilient material bent substantially in half to provide a pair of arms spaced from each other in superimposed aligned relationship adapted to grip a support therebetween, and means on one of said arms for slidably and frictionally receiving therein said raised husk portion.

55 3. In an electric light holder, a husk of insulating material having a portion thereof raised above the outer surface, an attaching member comprising a strip of resilient material bent substantially in half to provide a pair of arms adapted to grip a support therebetween, and means on one of said arms for slidably and frictionally receiving therein said raised husk portion, said last named means comprising a pair of 70 angularly bent tabs on said arm, adapted to

engage opposite edges of said raised husk portion.

4. In an electric light holder, a husk of insulating material having a portion thereof raised above the outer surface, said raised portion being provided with inwardly tapered longitudinal edges, an attaching member comprising a strip of resilient material bent substantially in half to provide a pair of arms adapted to grip a support therebetween, and means on one of said arms for slidably and frictionally receiving 10 therein said raised husk portion, said last named means comprising a pair of angularly bent tabs on said arm, adapted to engage said tapered edges of said raised husk portion.

15 5. In an electric light holder, a husk of insulating material having a portion thereof raised above the outer surface, an attaching member comprising a strip of resilient material bent substantially in half to provide a pair of arms adapted to grip a support therebetween, and means on one of said arms for slidably and frictionally receiving 20 therein said raised husk portion, said last named means comprising angularly bent over opposed longitudinal edges of said arm to define a guideway for receiving said raised 25 portion therein.

6. In an electric light holder, a husk of insulating material having a portion thereof raised above the outer surface, an attaching member comprising a strip of resilient material bent substantially in half to provide a pair of arms adapted to grip a support therebetween, at least one of said arms being provided with serrated or corrugated edges to facilitate the gripping of 30 said support, and means on one of said arms for slidably receiving therein said raised husk portion.

7. In an electric light holder, a husk of insulating material having a portion thereof raised above the outer surface, an attaching member comprising a strip of resilient material bent substantially in half to provide a pair of arms adapted to grip a support therebetween, at least one of said arms being provided with serrated or corrugated edges to facilitate the gripping of 40 said support, and means on one of said arms for slidably and frictionally receiving therein said raised husk portion, said last named means comprising angularly bent over opposed longitudinal edges of said arm to define a guideway for receiving 45 said raised portion therein.

8. In an electric light holder, a husk of insulating material having a portion thereof raised above the outer surface, an attaching member adapted to grip a support, comprising a strip of resilient material bent substantially in half to provide a pair of arms spaced from each other, and a substantially flat member rotatably attached to one of said arms, said last named member being provided with angularly bent over longitudinal edges adapted to define a guideway for 50 slidably and frictionally receiving said raised husk portion therein.

9. In an electric light holder, a husk of insulating material having a portion thereof raised above the outer surface, an attaching member comprising a strip of resilient material bent substantially in half to provide a pair of arms spaced from each other in superimposed aligned relationship adapted to grip a support therebetween, 70 means on one of said arms for slidably mounting said arm on said raised husk portion, and a bottom cap member threadedly attached to said husk, said cap member having a portion projecting beyond the said outer surface of said husk 75

- in the path of said last named slidable arm, and adapted to hold said slidably mounted attaching member captive on said husk.
10. In an electric light holder, a husk of insulating material having a portion thereof raised above the outer surface, an attaching member comprising a single longitudinal strip of resilient material bent substantially in half to provide a pair of arms spaced from each other in superimposed aligned relationship adapted to grip a support therebetween, and means on one of said arms for slidably and frictionally receiving said raised husk portion therein, and means on said last named arm for preventing the downward sliding movement of said attaching member.
15. In an electric light holder, a husk of in-

sulating material having a portion thereof raised above the outer surface, an attaching member comprising a strip of resilient material bent substantially in half to provide a pair of arms spaced from each other in superimposed aligned relationship adapted to grip a support therebetween, and means on one of said arms for slidably and frictionally receiving said raised husk portion therein, and means on said last named arm for preventing the downward sliding movement of 10 said attaching member, said last named means comprising a projection struck out from said arm and adapted to cooperatively engage the material of said raised portion.
